United States Patent Office.

FRANK B. JONES, OF LOUISVILLE, KENTUCKY.

Letters Patent No. 106,170, dated August 9, 1870.

IMPROVEMENT IN HINGES.

The Schedule referred to in these Letters Patent and making part of the same

To all whom it may concern:

Be it known that I, FRANK B. JONES, of Louisville, in the county of Jefferson and State of Kentucky, have invented a new and useful Improvement in Shutter-Hinge; and I do hereby declare that the following is a full, clear, and exact description thereof, which will enable others skilled in the art to make and use the same, reference being had to the accompanying drawing forming part of this specification.

This invention relates to a new and useful improvement in a butt-hinge for shutters, more especially designed for inside window-shutters, which have rebated edges, but which are applicable to other purposes; and it consists in making angles in the leaves of the hinge, so that the hinge shall conform to the edges of the shutters, as hereinafter more fully described.

In the accompanying drawing—

Figure 1 represents a side view of the hinge with the leaves extended.

Figure 2 is a cross-section of fig. 1, showing the angles by which the leaves are made to fit the rebate of the shutters.

Figure 3 represents the hinge attached to the shutters, showing the latter closed.

Similar letters of reference indicate corresponding parts.

The edges of inside window-shutters are rebated,

so that, when closed, the sections lap by each other and form an angular joint.

The butt-hinge ordinarily used for hinging them together is the common flat-leaved butt, placed flat upon the sides of the shutters, leaving the whole size of the hinge exposed to view, thus presenting an unsightly and clumsy appearance.

With a view of avoiding this appearance I construct my butt with an angle, A, in each leaf, which fits into the angle of the shutters, as seen in fig. 3, so that the joint edge of the butt only shows when the shutter is closed, as seen at B, in the same figure.

By this improvement, the butt is made to appear, when applied to rebated edges, the same as the ordinary butt when closed, thus giving a neat and workmanlike appearance to the closed shutters of a room, instead of an exhibition of a multitude of full sized butts and screw-heads.

Having thus described my invention,

I claim as new, and desire to secure by Letters Patent—

As an article of manufacture, the hinge A A B, formed with two right-angled bends on each leaf, to fit upon the rabbeted edges of the shutters, as shown in fig. 2 of drawing, and for the purpose specified.
